UNITED STATES PATENT OFFICE.

THOMAS SHEHAN, OF CLEVELAND, OHIO.

FLEXIBLE CORE FOR CASTING.

SPECIFICATION forming part of Letters Patent No. 223,820, dated January 27, 1880.

Application filed December 10, 1879.

To all whom it may concern:

Be it known that I, THOMAS SHEHAN, of Cleveland, in the county of Cuyahoga and State of Ohio, have invented certain new and useful Improvements in Mechanism for Casting Curved Metal Pipe; and I do hereby declare the following to be a full, clear, and exact description of the invention, such as will enable others skilled in the art to which it pertains to make and use it, reference being had to the accompanying drawings, which form part of this specification.

My invention relates to a device for casting curved metal pipe, and is especially adapted for the construction of lead-pipe joints, goose-necks, curves, &c.; and it consists of a flexible spring or elastic core, made in sections, and so connected as to be held in proper position and relation to each other by the action of a retaining-spring, which will also permit the component sections of said core being so shaped in their relation to each other as that the entire core shall be straight, or substantially so, either in part or as a whole, thus enabling it to be readily withdrawn from the casting after the metal has cooled and set without injury either to the casting or core, after which removal the spring shall operate to restore the component sections of the core to their original and proper position for reintroduction into the mold to be employed for a subsequent casting.

In the drawings, Figure 1 represents, partly in longitudinal section and partly in elevation, a mold and cores, according to my invention, for casting substantially such a device as the sewer-trap shown and described in Letters Patent No. 194,070, granted to B. P. Bower, August 14, 1877. Fig. 2 is a detached view, showing, in longitudinal section, the flexible spring-core in its closed position; Fig. 3, the same in its opened or straightened position, as it appears when being withdrawn from the finished casting.

A represents the walls of the mold proper, which may be of any suitable material or shape, according to the metal or article to be cast.

B is the flexible core considered as an entirety. B' are component joints or sections of the curved portion of the cone. B² are dowel-pins, suitably attached to suitable joints or

sections B', and engaging in opposite recesses of neighboring joints to accomplish the well-known office of dowel-pins, to wit, to hold in proper position and prevent from lateral displacement the various joints when brought together.

C is a continuous flexible line or chain passing freely through all the sections B' excepting the last one, to which it is connected in any suitable manner. The other end of this chain passes freely through the straight portion of the core B, and is attached to the bar C' or its equivalent.

It will be apparent that, as the bar C' is moved in a direction into or out of the cavity of the cone in which it is placed, it will alternately permit the sections B' to arrange themselves more or less into a straight line with the straight portion of the core, or draw them into close contact with each other, thus compelling them collectively to describe such a curve as shown in the drawings, or any other curve that might be determined by the peculiar conformation of the component sections B'.

A continuation of the core B (shown in the drawings at B³) is made to extend outside of and beyond the mold A. This portion is provided with a male screw-thread, with which engages the collar B⁴, having a female screw 80 to correspond with the thread B³. This collar B⁴ is provided with handles or any other suitable device whereby it may be conveniently manipulated, for purposes which will herein-after appear.

C² is a spring, the operation of which is to drive bar C' in a direction out from the core B, this tending at all times to maintain the sections B' in their closed position.

An important feature of my device is the section B⁵, that unites the straight portion of the core with the curved sections. A detached view of this section B⁵ is shown in Fig. 4 of the drawings. It consists, essentially, of a short tube or cylinder, b, having an enlarged end or flange, b', shaped properly to form the first joint or section of the curved portion of the core. The part b', however, may have, if desired, the surface of a plain straight cylinder corresponding to the straight portion of the core, instead of being curved, as above mentioned. The portion b enters and revolves within the lower

end of the straight portion of the core. This construction permits a free rotation of the straight portion of the core and all its attached parts, without any liability to disturbance of 5 of any other portion of the core. Moreover, it allows of sufficient longitudinal stretching or elongation of the core without detriment to the position or operation of the curved portion thereof.

10 The operation of my device is as follows: The parts having been arranged and adjusted substantially as shown in Fig. 1 of the drawings, or in any other relation suitable to the product to be cast, the metal is poured between 15 the wall of the mold A and the core B. When sufficiently cooled and set the core B is withdrawn from the casting and the casting removed from the mold.

The operation of withdrawing the core B may 20 either be accomplished by a direct manual pull upon its projecting portion B³, or the collar B⁴ may be screwed down in such a manner upon the casting or the mold A as will in an obvious manner operate to straighten and withdraw 25 the core B, after which the core is replaced in the mold, and everything is ready for a subsequent casting. In case of lead casting this operation may be repeated very rapidly, the mold and core being both composed 30 of metal and the lead rapidly cooling and setting.

Having thus described my invention, what I claim as new, and desire to secure by Letters Patent, is—

35 1. The combination, with a curved mold and a tubular core having a portion thereof formed with ring-sections, of a flexible device secured to the latter, and adapted to adjust them in or out of line with the rigid portion of the core, 40 substantially as set forth.

2. The combination, with a curved mold, a tubular core having a portion thereof formed with ring-sections, and fastening devices which 45 secure the latter together, of a flexible device secured to said sections and adapted to adjust them in or out of line with the rigid portion of the core, substantially as set forth.

3. The combination, with a curved mold, a tubular core having a portion thereof formed

50 with ring-sections, and fastening devices which connect the latter together, of a flexible device secured to said sections at one extremity and connected to a rod at its opposite extremity, said rod passing through the rigid portion of the core 55 and adapted to communicate force to said flexible device in adjusting the ring-sections in or out of line with the rigid portion of the die, substantially as set forth.

4. The combination, with a curved mold, a tubular core having a portion thereof formed 60 with ring-sections, and dowel-pins connecting the latter together, of a flexible device having one extremity secured to the last ring-section and the opposite extremity secured to a rod which passes through the rigid portion of the 65 core, substantially as set forth.

5. The combination, with a curved mold and a tubular core having a portion thereof formed with ring-sections, of a chain having one extremity secured to the last section and its opposite extremity secured to a rod which passes through the rigid portion of the core, together with a spring which actuates said rod in drawing out the chain, and thereby forcing the ring-sections out of line with the rigid portion of 75 the core, substantially as set forth.

6. In a tubular core, the combination, with the rigid portion, of a flexible portion composed of ring-sections, and an intermediate tube, said tube being formed with a straight portion 80 which fits in the rigid portion of the core, and provided with an enlarged projecting end which connects with the ring-sections, substantially as set forth.

7. The combination of sections B', dowel-pins B², chain or line C, bar C', and spring C², 85 substantially as and for the purposes shown.

8. In combination with the core B, the projecting portion B³ and the collar B⁴, substantially as and for the purposes shown. 90

In testimony whereof I have signed my name to this specification in the presence of two subscribing witnesses.

THOMAS SHEHAN.
